UNITED STATES PATENT OFFICE

1,996,445

DUPLICATOR

Ludwig W. Wagner, Chicago, Ill., assignor to
S. Eugene Miller, Aurora, Ill.

Application April 29, 1933, Serial No. 668,615

9 Claims. (Cl. 101—131)

My invention relates generally to duplicating machines and particularly has to do with a light weight portable machine, of which the primary object thereof is to provide a construction embodying a table or container plate for supporting a compound and a cover for the table, the cover providing means enabling an operator of the machine to slide the cover back to allow the sheet, to be printed, to gradually engage the compound, and upon the return movement of the cover to cause the cover to act as a stripper separator for stripping or separating the printed sheet from the compound.

Another object is to provide the upper edges of the side edges of the table or container plate with rails, and also provide the edges of the cover with means for engaging the rails in a manner to slidably connect the cover to the table, the cover being detachable only when withdrawn in a longitudinal direction from either end of the table.

A further object of my invention is to provide a durable substantially flat machine which is simple in design and which may be economically manufactured. A further object is to provide a machine of the kind described which is provided with a supply of composition pads so that there is always one or more pads available for further duplicating of additional work.

30 The invention has among its further objects the production of a device of the kind described that is simple, inexpensive, compact, efficient and satisfactory for use wherever found applicable.

Many other objects and advantages of the construction herein shown and described will be obvious to those skilled in the art from the disclosure herein given.

To this end, my invention consists in the novel construction, arrangement and combination of parts herein shown and described, and more particularly pointed out in the claims.

Referring to the drawings, in which like reference characters indicate like or corresponding parts:

45 Fig. 1 is a top plan view showing the general arrangement of the device;

Fig. 2 is a transverse sectional view taken substantially on line 2—2 of Fig. 1;

50 Fig. 3 is a longitudinal sectional view taken substantially on line 3—3 of Fig. 1;

Fig. 4 is an enlarged sectional view showing the construction of a side of the device;

55 Fig. 5 is a similar enlarged sectional view showing the pad retaining clamp;

Fig. 6 is a transverse cross sectional view showing a modified form of pad container;

Fig. 7 is a top plan view of another modified construction; and

Fig. 8 is a sectional view taken substantially on line 8—8 of Fig. 7.

Referring to the drawings, particularly Figs. 1 to 5, 1 is a plate or container, preferably of metal or the equivalent, formed with the flanged sides

2 which are preferably extended over as at 3 and 10.

thence back and outwardly as at 4, so as to form a receptacle with rails or guides at the sides, which in the construction shown is open at both ends. The same may be provided with feet 5—5

of rubber or equivalent cushioning material. Arranged within the receptacle described is a compound 6 which is preferably mounted on a sheet

6' of fabric, the fabric being longer than the length of the compound body. As shown, the same is extended with the extreme ends 7 folded

over the end of the bottom plate 1. The ends of the fabric are secured in place by clamping members each consisting of the plate 8, which is preferably provided with a flange or stop 9, the opposite end bent over as at 10 and 11 so as to

20 clamp the fabric end to the receptacle, thereby securing the pad in place. The flange 9 forms an end at each end of the pad and also serves as a paper guide at one or either end. Arranged over

the pad is a cover or stripping plate 12 which is provided with a flange 13 at either side (see Fig.

4) so that the same is held in place but may be slidably moved over the compound or composition pad. When the device is not in use the cover

12 serves as a cover to protect the pad, and when

the device is being used the same serves as a paper stripper, stripping the paper which has

been printed upon the pad so that the same comes off of the pad without rolling. In other words, it

is stripped off and remains flat.

It is hardly necessary to describe in detail how the device duplicates, it being understood that in

the first instance a sheet is provided with suitable writing, printing, drawing or the like thereon made with copying ink, pencil, colors or the

like, and this arranged and pressed firmly and evenly on the pad which has been previously moistened. This sheet is then removed, leaving

the impression in negative or reverse on the pad and from this the duplicate copies are made. It

is desirable that the original to be reproduced be brought in contact with the composition pad by

means of the sliding cover. The blank paper fed

afterwards in the same manner assures satisfactory registration. The duplicate copies are laid

on the pad and pressed down by hand or roller and then removed.

As before mentioned, when a sheet is pulled from the pad, the character of the pad and moisture causes a tendency of the sheet to roll up and not lie flat, so that the printed or duplicated sheets are difficult to handle and will not properly stack unless held down. With the present device, referring to Fig. 3, the sheet of paper 14 is applied to the pad at the end 15 of the paper which may contact with the stop 9 or flange to guide the same. The sheet is then pressed down on the pad, the cover 12 being moved to a point where only the end 16 is on the cover. After the desired interval the cover is pushed back toward the end 15 of the paper, the end 16 being retained. The cover 12, sliding under the paper, lifts or strips the same from the pad, as will be obvious by reference to Fig. 3, so that the paper comes off perfectly flat. The operations are continued until the desired number of copies are secured.

In the construction shown in Fig. 6, the operation of duplicating is similar, but in this instance the pad construction is modified. As shown, 29 represents the bottom of a receptacle or container plate provided with side walls 21 and open ends. The side walls are preferably flanged over as indicated at 22 to form slides or guides for the cover or stripper plate 26 which is provided with the engaging turned over edges 27. In this construction 24 represents one or more shallow pans or trays which contain a compound 25, either mounted on fabric or arranged directly in the pan as desired. The receptacle 29 is arranged to carry one or more pads, that shown being adapted to carry two, one or more additional receptacles and pans being arranged below and supporting the top one 20. The several units may be arranged to slidably connect together so that they may be interchanged. The stripper plate 26, as before mentioned, is slidable and the paper may be applied or stripped from the pad in the same manner as set forth in the apparatus shown in Figs. 1 to 5.

Figs. 7 and 8 shows another construction which is substantially similar, except that there is provided a pressure roller and the pad is arranged on the flat plate 30. Referring to this construction, 31 represents feet or cushion for the bottom of the plate 30 upon which is arranged the pad 32. A pressure roller 33 is connected by a link 34 at 35 to the sides 37 of a paper support or table 36. Table 36 is supported by the legs 38 which slidably engage the edges of the plate 30. The paper sheet 39 is laid on the table 36 with the end 40 extending beyond the pad 32. As the roller and table 36 are moved, for example to the right, the paper is rolled down on the pad 32 and just before the end 41 of the paper drops off the table 36, the table and roller are moved in the opposite direction, stripping the paper from the pad.

It is believed that the construction and operation of the device as shown will be clearly understood from the preceding description. With all of the constructions shown the paper may be removed from the pad by the stripper plate or cover which is slidably mounted above the pad.

Having thus described my invention, it is obvious that various immaterial modifications may be made in the same without departing from the spirit of my invention; hence, I do not wish to be understood as limiting myself to the exact form, construction, arrangement and combination

of parts herein shown and described, or uses mentioned.

What I claim as new and desire to secure by Letters Patent is:

1. In a machine of the kind described, a table provided with rails, a compound arranged on said table between said rails, a cover member engageable with said rails and operatively related to said table in a manner whereby to apply a sheet to said compound when said member is moved in one direction and when moved in another direction providing means for separating and removing said sheet from said compound. 5

2. In a machine of the kind described, a table including a compound arranged thereon, and a cover member slidably related to said table in a manner whereby to apply a sheet to said compound when moved in one direction and when moved in the opposite direction providing means for separating and removing said sheet from said compound. 10

3. In a machine of the kind described, a table having side walls providing rails, a compound arranged on the table between said rails, and a cover slidably secured to said rails of a character 25 to remove a sheet previously applied to the compound.

4. In a machine of the kind described, a table providing a support for a compound associated therewith, and a cover secured to said table and operable to assist in applying a sheet and removing it from the compound. 30

5. In a machine of the kind described, a table including a compound arranged thereon, and a cover secured to said table and longitudinally 35 operable to assist in gradually applying a sheet and removing it from the compound.

6. In a machine of the kind described, a table including a compound arranged thereon, and a cover slidably related to said table providing 40 means when moved in one direction for applying a sheet to the compound and when moved in the opposite direction providing means for separating and removing said sheet from said compound.

7. In a machine of the kind described, a table, 45 a plurality of interchangeable trays arranged on said table one above the other and each containing a compound, and a cover member operatively related to said table providing means for gradually applying a sheet to the compound 50 in the upper tray and also providing means for separating and removing said sheet from said compound.

8. In a machine of the kind described, a table provided with upper rails and lower rails and 55 providing a support for one or more trays each containing a compound, a member engageable with said upper rails and operable with respect to said table and compound for applying a sheet to said compound and also providing means for separating and removing said sheet from said compound, and said lower rails providing legs for said table and also providing means for receiving the upper rails of another like table whereby a plurality of tables may be slidably associated with 60 each other.

9. In a machine of the kind described, a table including a compound arranged thereon, and a substantially flat member arranged in close spaced parallel relation to said table operatively 70 related to said table for applying a sheet to said compound and thence removing it therefrom.
